(57) **CLAIM**

The ornamental design for exterior compartment of a handbag for an article such as a mobile phone, eyeglasses or the like, as shown and described.

DESCRIPTION

FIG. 1 is a top and left side perspective view of a first embodiment of an exterior compartment of a handbag for an article such as a mobile phone, eyeglasses or the like shown open in opposition of use;

FIG. 2 is an enlarged top plan view thereof shown in a closed position;

FIG. 3 is a front view thereof;

FIG. 4 is a left side view thereof, the right side being a mirror image;

FIG. 5 is a bottom plan view thereof;

FIG. 6 is a top and left side perspective view of a second embodiment of an exterior compartment of a handbag for an article such as a mobile phone, eyeglasses or the like shown open in position of use;

FIG. 7 is an enlarged top plan view thereof shown in a closed position;

FIG. 8 is a front view thereof;

FIG. 9 is a left side view thereof, the right side being a mirror image;

FIG. 10 is a bottom plan view thereof;

FIG. 11 is a top and left side perspective view of a third embodiment of an exterior compartment of a handbag for an article such as a mobile phone, eyeglasses or the like shown open in position of use;

FIG. 12 is an enlarged top plan view thereof shown in a closed position;

FIG. 13 is a front elevational view thereof;

FIG. 14 is a left side view thereof, the right side being a mirror image;

FIG. 15 is a bottom plan view thereof;

FIG. 16 is a top and left side perspective view of a forth embodiment of an exterior compartment of a handbag for an article such as a mobile phone, eyeglasses or the like shown open in position of use;

FIG. 17 is an enlarged top plan view thereof shown in a closed position;

FIG. 18 is a front elevational view thereof;
FIG. 19 is a left side view thereof, the right side being a mirror image;
FIG. 20 is a bottom plan view thereof;
FIG. 21 is a top and left side perspective view of a fifth embodiment of an exterior compartment of a handbag for an article such as a mobile phone, eyeglasses or the like shown open in position of use;
FIG. 22 is an enlarged top plan view thereof shown in a closed position;
FIG. 23 is a front elevational view thereof;
FIG. 24 is a left side view thereof, the right side being a mirror image;
FIG. 25 is a bottom plan view thereof;
FIG. 26 is a top and left side perspective view of a sixth embodiment of an exterior compartment of a handbag for an article such as a mobile phone, eyeglasses or the like shown open in position of use;
FIG. 27 is an enlarged top plan view thereof shown in a closed position;
FIG. 28 is a front elevational view thereof;
FIG. 29 is a left side view thereof, the right side being a mirror image;
FIG. 30 is a bottom plan view thereof;
FIG. 31 is a top and left side perspective view of a seventh embodiment of an exterior compartment of a handbag for an article such as a mobile phone, eyeglasses or the like shown open in position of use;
FIG. 32 is a front elevational view thereof shown in a closed position;
FIG. 33 is a top plan view thereof;
FIG. 34 is a left side view thereof, the right side being a mirror image;
FIG. 35 is a bottom plan view thereof;
FIG. 36 is a top and right side perspective view of an eighth embodiment of an exterior compartment of a handbag for an article such as a mobile phone, eyeglasses or the like shown open in position of use;
FIG. 37 is a front elevational view thereof;
FIG. 38 is a top plan view thereof;
FIG. 39 is a left side view thereof, the right side being a mirror image;
FIG. 40 is a bottom plan view thereof;
FIG. 41 is a top and right side perspective view of a ninth embodiment of an exterior compartment of a handbag for an article such as a mobile phone, eyeglasses or the like shown open in position of use;
FIG. 42 is an enlarged top plan view thereof shown in a closed position.
FIG. 43 is a top plan view of the compartment shown in FIG. 42 in the closed condition, with a portion of the handbag shown in dotted lines for environmental purposes only;
FIG. 44 is a left side view thereof, the right side being a mirror image; and,
FIG. 45 is a bottom plan view thereof.
The broken line showing of a handbag is for illustrative purposes only and forms no part of the claimed design.
